UNITED STATES PATENT OFFICE.

MARY E. HESS, OF FORISTELL, MISSOURI.

REMEDY FOR COUGHS, &c.

SPECIFICATION forming part of Letters Patent No. 445,470, dated January 27, 1891.

Application filed May 29, 1890. Serial No. 353,632. (No specimens.)

To all whom it may concern:

Be it known that I, MARY E. HESS, a citizen of the United States of America, residing at Foristell, in the county of St. Charles and State 5 of Missouri, have invented certain new and useful Improvements in a Cough-Cure; and I do hereby declare the following to be a full, clear, and exact description of the invention, such as will enable others skilled in the art to which 10 it appertains to make and use the same.

My invention has relation to fluid medicine compounds or mixtures for the alleviation and cure of affections of the chest and lungs; and it consists in a decoction formed of several 15 herbs and combined with sugar, as will be hereinafter fully set forth.

To prepare this compound or cough-sirup, I take one-half pound of mullein-leaves, (*Verbascum*), one pound of pennyroyal, (*Hedeoma pulegioides*), one quarter of a pound of sage, (*Salvia*), four ounces of savory, (*Satureia*), and one pound of white sugar. These ingredients, with the exception of the sugar, are placed in a porcelain kettle with sufficient

water to cover them and are boiled for two or 25 three hours, and the decoction formed therefrom is then taken out and strained and the sugar put in, after which it is boiled down to a proper consistency, when the bulk will have been reduced to one-quarter. The herbs entering into the above compound are used 30 when green; but, if necessary, they can be weighed while green and dried before the decoction is made therefrom.

Dose: For an adult I recommend in case 35 of severe coughs and colds a table-spoonful every hour.

I claim—

A medical compound or cough-sirup made up of a decoction of mullein-leaves, pennyroyal, sage, and savory, with water and sugar, in about the proportions set forth. 40

In testimony whereof I affix my signature in presence of two witnesses.

MARY E. HESS.

Witnesses:

A. G. PRINGLE,
Mrs. G. P. STRONG.
